UNITED STATES PATENT OFFICE.

TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

ELECTROMAGNETIC RELAY.

Application filed December 9, 1920. Serial No. 429,547.

To all whom it may concern:

Be it known that I, TALBOT G. MARTIN, a citizen of the United States of America, and a resident of Chicago, Cook County, and 5 State of Illinois, have invented certain new and useful Improvements in Electromagnetic Relays, of which the following is a specification.

The present invention relates in general 10 to electro-magnetic relays but more particularly to such relays as are known as gang or multiple contact relays, and the object of the invention may be stated to be, specifically, the provision of a multiple contact relay of improved design that is rugged in construction, permanent in adjustment, and economical to manufacture.

The construction of the improved relay 20 will be fully described hereinafter, reference being had to the accompanying drawings, of which Fig. 1 is a side elevation, with one of the relay coils drawn in dotted lines to expose the parts behind it, while Fig. 2 is a similar view from the other side with some 25 of the parts cut away to more clearly show the construction. Fig. 3 is a detailed view of certain of the contacts.

Referring now to the drawings, the relay 30 comprises two coils 3 and 4 which are fastened by means of two screws to yoke 9. Yoke 9 is fastened by means of two other screws to the frame 2. The armature 15, most clearly seen in Fig. 2, is pivoted to yoke 10 by two pointed pivot screws 7 35 and 8 which fit into two holes in armature 15. The yoke 10 is secured to yoke 9 by means of two screws as is clearly seen in the drawings. Insulated alike from each other and from armature 15 and mounted 40 on the latter are two thin plates 5 (Fig. 1) and 6 (Fig. 2) which are made of springy material. The plates 5 and 6 and their insulation are clamped tightly on opposite sides of armature 15 between the two clamping pieces 11 and 12 by means of screws 45 16 and 17. The plates 5 and 6 have a number of radially extending projections, as the drawings clearly show, whose function is to make electrical contact with the contacts such as 31 and 32 (Fig. 1) and 41 50 and 42 (Fig. 2) secured to the frame 2, whenever the armature 15 is attracted by coils 3 and 4. The afore-mentioned contacts are insulated from each other and from 55 the frame and are arranged in two semi-

circular rows, as is clearly seen in the drawing, and the two rows are spaced a short distance apart by semi-circular spacing plates placed between them. It may be stated that the contacts are arranged and 60 built up like the bank contacts of the well known rotary line switch. The two rows of contacts, their insulation, and spacing plates are clamped tightly together between clamping plate 1 (Fig. 1) and frame 2 by 65 means of screws 24-30, inclusive. Projection 21 of plate 5 and projection 23 of plate 6 are bent to such an extent that they are always touching contacts 20 and 22, respectively, (see Fig. 3) and act against them 70 as springs to keep armature 15 back against the adjustable back-stop screw 18 when the relay is not energized. All the other projections of plates 5 and 6, however, are normally separated a short distance from their 75 associated contacts.

The description of the mechanical features of the invention, having been finished, will now be succeeded by an explanation of how the relay operates.

A suitable circuit for the coils 3 and 4 is provided and may be closed and opened by a key, another relay, or any well known or preferred means. The circuit, of course 80 contains a source of current. When said circuit is closed the coils 3 and 4 energize and attract armature 15 which displaces plates 5 and 6 a sufficient amount so that all the projections of said plates are caused to engage with their respective associated 85 contacts. When the circuit for the relay is opened, coils 3 and 4 lose their magnetism and the armature 15, propelled by the aforementioned projections of plates 5 and 6 acting as springs against contacts 20 and 22, 90 moves back to its original position against the back-stop screw 18.

One special case in which the present invention is well adapted to function will 95 now be briefly explained. It is often desirable in an automatic telephone exchange to make a large number of trunks busy at the same time. This is accomplished, as is well known, by grounding the private conductors of the respective trunks. We may wire 100 the private conductors of fifty trunks to the fifty contacts of the relay shown in the present disclosure, excluding contacts 20 and 22, which contacts will be connected to ground. Now when the relay operates 105

upon the closure of its circuit, ground is placed upon each and every one of the fifty private conductors wired to the contacts thereof, thus making the fifty trunks busy.

5 Having described my invention, what I consider to be new and desire to have protected by Letters Patent will be pointed out in the appended claims.

What I claim as my invention is:

- 10 1. In an electro-magnetic relay, a plurality of fixed contacts, said contacts being insulated from each other, a plurality of independent flexible movable contacts, said movable contacts being punched from a single sheet of material and left attached thereto, and electro-magnetically controlled means for simultaneously bringing all said movable contacts into electrical contact with said stationary contacts.
- 15 2. In an electro-magnetic relay, a plurality of groups of fixed contacts, each of said contacts being insulated from all the rest, a plurality of groups of independently flexible movable contacts, each group of said movable contacts being punched from a single sheet of material and left attached thereto, and electro-magnetically controlled means for simultaneously bringing all said movable contacts into electrical contact with said fixed contacts.
- 20 3. In an electro-magnetic relay, a plurality of fixed contacts arranged in an arcuate row, a resilient member having a plurality of radially extending projections adapted to engage said fixed contacts, one of said projections being normally in engagement with one of said fixed contacts and serving as a spring to maintain the other projections out of engagement with said contacts, and

an armature for operating said member to cause all of said other projections to engage their associated fixed contacts.

4. As an article of manufacture, a relay comprising a bank of fixed contacts arranged in a plurality of arcuate rows, a resilient member for each of said contact rows having a series of radially extending projections adapted to engage the fixed contacts in the associated row, a magnet, and a single armature for operating all said members to cause all said projections to simultaneously engage their associated fixed contacts.

5. In an electro-magnetic relay, a bank of fixed contacts, and a contact plate having a plurality of fingers, one for each corresponding fixed contact, one of said fingers continuously engaging its corresponding fixed contact to maintain the remaining contacts disengaged, and an armature for operating said contact plate to overcome the tension of the continuously engaged finger to cause the remainder of said contacts to also become engaged.

6. An electro-magnetic relay having a semi-circular row of fixed contacts, a semi-circular row of movable contacts, an armature for bringing certain of said movable contacts into engagement with said fixed contacts in pairs when the relay is energized, other of said contacts normally preventing the said certain contacts from engaging the fixed contacts, and a single adjusting means for simultaneously varying the distance between said rows of contacts.

Signed by me at Chicago, Cook County, Illinois this 4th day of December, 1920.

TALBOT G. MARTIN.
